UNITED STATES PATENT OFFICE.

JOSEPH TRACY, OF NEW YORK, N. Y.

COMBINED EXHAUST-VALVE AND IGNITER.

SPECIFICATION forming part of Letters Patent No. 722,544, dated March 10, 1903.

Application filed October 21, 1902. Serial No. 128,130. (No model.)

To all whom it may concern:

Be it known that I, JOSEPH TRACY, a citizen of the United States, and a resident of the city of New York, borough of Manhattan, in the county and State of New York, have invented new and useful Improvements in a Combined Exhaust-Valve and Igniter, of which the following is a full, clear, and exact description.

10 This invention relates to improvements in combined exhaust-valves and igniters for combustion-engines; and the object is to provide an exhaust-valve with a simple, inexpensive, and reliable means for igniting the charge of combustion agent.

I will describe a combined exhaust-valve and igniter embodying my invention and then point out the novel features in the appended claims.

20 Reference is to be had to the accompanying drawings, forming a part of this specification, in which similar characters of reference indicate corresponding parts in both the figures.

25 Figure 1 is a sectional view of a portion of a combustion-engine, showing combined exhaust-valve and igniter embodying my invention as applied thereto; and Fig. 2 is a longitudinal section of the valve.

30 Referring to the drawings, 1 designates the combustion-chamber of an engine, which communicates with the usual exhaust-port 2. This exhaust-port is controlled by a valve 3, the stem 4 of which passes through a guide 5.

35 The inner end of the stem is provided with a longitudinal bore 6, which forms a chamber for the entrance of gas and air. In the mouth of the bore is a threaded plug 7, having a perforation 8, which forms a restricted outlet for

40 the enlarged bore or chamber 6. This restricted outlet is not required in all cases; but it is preferable in fast-running engines where a quick outflow of flame and quick ignition are required, and of course the perfora-

tion may be made of any size to suit conditions. 45

The operation is as follows: After the engine has been in operation a short time the valve-stem becomes heated by the exhaust to a sufficient degree to ignite the combustion agent. When the charge of gas and air is admitted to the combustion-chamber 1, a portion thereof will enter the bore of the valve-stem, where it will be immediately ignited, and the flame will discharge into and ignite 50 the large body of gas and air in the combustion-chamber of the engine.

It will be seen that a device embodying my invention is very simple in its arrangement and construction, and there are no extra parts 60 or additions carried by the valve that would be liable to be broken or that would add expense to the valve construction.

Having thus described my invention, I claim as new and desire to secure by Letters 65 Patent—

1. A combustion-engine exhaust-valve, having a longitudinal bore in its stem forming an igniting-chamber opening into the combustion-chamber. 70

2. A combustion-engine exhaust-valve, having a longitudinal bore in its stem forming an igniting-chamber opening into the combustion-chamber, the said bore being restricted at its mouth. 75

3. A combustion-engine exhaust-valve, having a longitudinal bore in its stem, and a plug removably placed therein, the said plug having a perforation providing communication between the bore and the combustion-chamber of the engine. 80

In testimony whereof I have signed my name to this specification in the presence of two subscribing witnesses.

JOSEPH TRACY.
